United States Patent Office

Des. 215,311

Patented Sept. 23, 1969

215,311

TUBE HOLDER

Robert E. Born, 4111 St. Charles Road,
Bellwood, Ill. 60104

Filed Oct. 1, 1968, Ser. No. 13,804

Term of patent 3½ years

Int. Cl. D6—01

U.S. Cl. D33—22

Fig. 1

Fig. 2

Fig. 3

Fig. 4

Fig. 5

FIG. 1 is a top plan view of the tube holder embodying my new design;

FIG. 2 is a rear elevational view thereof;

FIG. 3 is a front elevational view thereof;

FIG. 4 is a side elevational view thereof, the opposite side being identical to the side shown; and

FIG. 5 is a bottom plan view thereof.

I claim:

The ornamental design for a tube holder, as shown and described.
